UNITED STATES PATENT OFFICE.

CHARLES McGREGOR, OF DERRY, NEW HAMPSHIRE; JENNIE B. McGREGOR, ADMINISTRATRIX OF SAID CHARLES McGREGOR, DECEASED, ASSIGNOR OF ONE-THIRD TO HENRY W. BLAIR, OF MANCHESTER, NEW HAMPSHIRE, AND ONE-THIRD TO JOHN C. McGREGOR, OF NASHUA, NEW HAMPSHIRE.

AIR-MOTOR.

1,281,618.

Specification of Letters Patent. Patented Oct. 15, 1918.

Application filed February 3, 1912. Serial No. 675,262.

To all whom it may concern:

Be it known that I, CHARLES McGREGOR, a citizen of the United States, residing at Derry, in the county of Rockingham and 5 State of New Hampshire, have invented certain new and useful Improvements in Air-Motors; and I do hereby declare the following to be a full, clear, and exact description of the invention, such as will enable 10 others skilled in the art to which it appertains to make and use the same.

The invention relates to wind motors, and it relates more especially to the oscillating type of wind motors, having certain characteristics analogous to those embodied in 15 my patent, Serial No. 717,110, dated December 30, 1902.

An object of the invention is to provide a device of this character that is simple of 20 construction, economical from the point of manufacture and maintenance and thoroughly efficient in operation.

A further object of the invention is to provide means associated therewith where- 25 by it will protect itself, automatically against unusually strong currents of wind and will be operated by comparatively moderate currents.

A still further object of the invention is 30 to obviate the necessity for lubricating the principal working parts of the motor.

A still further object is to provide means by which the motor may be manually operated when there is no wind current.

35 Other objects and advantages will be hereinafter set forth and claimed.

In the accompanying drawings, in which similar reference characters designate similar parts throughout the several views,

40 Figure 1 is an elevation view of the motor as viewed from the direction counter to the wind current.

Fig. 2 is a side elevation view thereof.

Fig. 3 is a fragmental detail perspective 45 view of the vane shown in Fig. 2.

Fig. 4 is a vertical sectional view taken on line 4—4 of Fig. 1.

Fig. 5 is a fragmental detail sectional view 50 through the supporting frame or tower, showing the rocker member and its adjuncts.

Fig. 6 is a detail perspective view of the

blade shifting lever and the means for holding it out of operative position.

Fig. 7 is a view in elevation and partly in section of a modified form of the invention. 55

Fig. 8 is a vertical sectional view on the line 8—8 of Fig. 7.

Fig. 9 is a vertical sectional view on the line 9—9 of Fig. 7, and,

Fig. 10 is a detail sectional view, showing 60 the wind operated and weighted lever hereinafter described.

Referring more particularly to Fig. 1 of the drawings, the tower or support for the wind motor is represented by the numeral 65 11, supporting the apertured block 12 on which is rotatably seated a table 13, preferably through the medium of a vane supporting beam 15. A rocker 14 is movably seated on the table. The table 13 and beam 70 15 are apertured and are preferably connected together by means of a hollow cylinder 16 which extends down through the aperture of the block 12 and thereby pivotally connects the table and block. 75

Secured to the lower central part of the rocker 14 is a supporting hook or the like 17 from which is suspended a link 18, which is adapted to connect with a pump or other device (not shown) to be operated. 80

Secured to the rocker by bolts or the like, as at 19 are the lower beams 20 of a truss frame, an upper beam 21 being secured thereto at 22, and to this frame, which normally rests in approximately horizontal position, are secured the sails which are designated 23. These sails consist of perforated standards 24, secured to the said truss frame, and a series of horizontally disposed blades 25 pivoted at 26 in the apertures of the 85 standards. The blades, in this embodiment of my invention, are provided with a pivot 27 which engages a series of apertures in the vertically disposed and vertically movable shifting rod 28, through the medium of 90 which the blades 25 may be shifted from one to the other of two oppositely inclined positions or planes. 95

The shifting mechanism for the blades consists in a pair of bell cranks 29 and 30 100 pivotally connected to the truss frame at 31 and 32 respectively, and connected together

by a link 33. The bell crank 30 is pivotally secured, at 34, to one of the shifting rods 28 by means of a link 35. The bell crank 29 is pivotally secured at 36 to the other shifting rod by means of a link 37.

The bell crank 29 is provided with a weight 38 for the purpose to be hereinafter specified.

The operation of this motor is as follows:

Considering Fig. 2, the arrow *a* indicating the direction of the wind, it is seen that the vane 39', supported by the beam or arm 15, retains the sail 23 in a plane at right angles 15 to the direction of the wind. It is seen that the blades 25 are pointing downward and rearward, or are inclined in the direction of the lower part of the vane. It is obvious that the force of the wind against the inclined surfaces of the blades will tend to 20 raise the blades, the sail and the end of the truss frame. The blades of the other sail are inclined in the opposite direction or toward the upper end of the vane, and it is 25 obvious that the wind current would tend to force the last said blades and sail downward. It requires but a slight current to cause the sails to yield to their respective tendencies, thereby moving the truss frame to a considerable angle from the horizontal position 30 shown. When the truss frame has become inclined to a certain predetermined angle, the lever 29 will move therewith, carrying the weight 38 past the pivotal point 31, and 35 when it is past said pivotal point to a sufficient extent, the weight and lever will be moved through the force of gravity to the other of its two extreme positions, and through the medium of the link 37 will 40 cause the shifting bars to change their respective positions and to dispose the blades at different and opposite angles.

It is obvious that this shifting of the blades will cause the wind current to move 45 the respective sails in the opposite direction. The bell crank 29 will again carry the weight 38 vertically over the pivot 31, the blades will again be shifted and the operation described will be repeated so long 50 as the wind current is sufficient and the blades are allowed to assume their respective angles.

As the truss frame oscillates, it is obvious 55 that the rocker 14 will continually rock back and forth on the table 13 and will cause the hook 17 and connecting link 18 to reciprocate vertically. It is obvious that the greater the oscillatory stroke of the truss frame, the greater the reciprocatory 60 stroke of the link 18, and consequently, the greater the power exerted and work accomplished. It is therefore desirable to have the frame work with the longest possible stroke; and in carrying out this object I 65 have provided an automatic tensioning

mechanism which consists of a lever 39 pivoted at 40 to the truss frame and connected by a link 41 to one of the shifting bars 28. The lever 39 carries a heavy plate 42 at its upper end, said plate being movably secured on the lever 39 by means of a set screw 43. It is obvious that the plate 42 acts, by gravity and by the force of wind thereagainst, for pressing the lever 39, and coacting with the link 41, for holding the 75 shifting-rod 28 in closed position and thereby exerting a resistance, which counteracts the tendency of the members 29 and 38 to move the shifting rod 28 from one to the other of its normal positions. When the 80 wind current increases the pressure upon the plate 42 is thereby increased, and the motion resisting effect upon the members 29 and 38 is increased, which results in the truss frame having to make longer oscillatory strokes than when the wind pressure is slight. It is therefore obvious that while the motor accomplishes more work, it is not caused to move with appreciably increased speed, but by making longer strokes. The 85 speed may be predetermined and regulated by employing the plate 42 of greater or less size and weight, and by shifting the plate 42 up or down on the lever 39, as circumstances may demand.

For the purpose of throwing the motor out of operation when desired, I have provided a neutralizing mechanism which consists of a stop member 44, pivoted at 45 to the upper beam 21 and has a horizontal extension 46 pivoted at 47, terminating in a lever 48, to which is connected, at 49, an operating member 50, which may be of any proper construction or material. The member 44 is provided with a loop 45' which is 100 adapted to receive the lever 29 and to hold it in a medial position between its two extreme positions, and thereby to hold each of the horizontal blades 25 on a horizontal plane; thus allowing the wind current to 105 pass freely through the sails, whereupon the oscillation of the sails and frame will cease. In operating the stop member 44 it is only necessary to raise the member 50, thereby causing the stop member to contact with the lever 29 which will fall into the loop 45' at the proper time. This result may be accomplished either by raising the member 50 by hand, or said member 50 may be connected in any proper and well known 110 manner with a float (not shown).

Any proper form of blades 25 may be employed, but I prefer the form shown in Fig. 6, in which the pivots 26 and 27 have hook ends 26^a passing through apertures in the blades and a supporting a loop or strap 26^b embracing the blade and pivots for holding them firmly together and for strengthening the blade 25.

The arm 15 is provided at its rear end 130

- with a standard 51 having an aperture 52 near its upper end. Secured to the rocker 14, and standing at right angles thereto is the rocker shaft or pivot brace 53, said brace 5 being loosely pivoted in the standard 51, and adapted to oscillate and to rock with the rocker and truss frame and to aid in supporting the truss frame and hold the sails in their vertical positions.
- 10 The vane 39' is provided with an auxiliary vane or air cushioning plate 54, standing on a plane perpendicular to that of the vane 39', and by the use of this auxiliary vane it has been found that the motor is 15 held much more steady than when it is omitted.

It may be desirable at times, when there is no wind current, to operate this wind motor by manually operated means, and such 20 means may consist of a rod or the like 55 by which the truss frame may be caused to oscillate by a person alternately pulling and pushing on the rod 55.

In lieu of the form of motor described in 25 the foregoing I may employ a somewhat modified form, in which I provide a solid beam 56, instead of the truss frame, to which the sails are secured. In this modification the blades 25' are substantially the same as 30 the blades 25, but instead of being pivoted at their ends are hinged to standards 24', secured to the beam 56. The blades are also hinged to a shifting rod 28'. These shifting rods are connected by a tension rod 57, 35 through the medium of which a pressure is brought to bear upon the shifting rods for tending to hold the blades in closed position. A bracket 58, secured to the beam 56 constitutes a bearing for the pivot 59 of a 40 tensioning lever 60, the lower end 61 of which bears upon the tension rod 57. Secured on the upper end of the lever 60 is a plate 62, adapted to receive the force of the wind current and to impart a proportional 45 pressure upon the rod 57. The pressure may also be regulated by means of the weight 63, which may be moved up or down on the lever 60 and secured at the desired point by means of a set screw 64.

50 Instead of the shifting mechanism described, I may employ a shifting beam 65, which is pivotally supported at 66 by means of T-shaped brackets 67, secured thereto. The beam 65 is connected to the shifting 55 rods 28' through the medium of links 68 and eye-bolts 69, the latter being rigidly secured to the shifting rods 28' and extending under the blades 25'. The links 68 are passed through apertures 70 in the beam 56, and 60 it is obvious that when the frame and sails oscillate, the T-shaped bracket 67 will oscillate on its pivot 72, carrying with it the beam 65. That is, the T-brackets and beams 65 will tend to retain their normal positions, and there will be a relative movement 65

between the beams 56 and 65, which will result in moving the links 68 and shifting rods 28' vertically, and thereby changing inclination of the blades 25'.

It is obvious, from the foregoing description of the lever 60 and tension rod 57, that the pressure exerted thereby on the shifting rods 28' will retard the shifting action of the blades 25' to such an extent that the beam 56 and sails oscillate with a longer 75 stroke, because the stroke continues until the blades are shifted.

It is obvious that the general principles and operation of this modified form are similar to those described for the other form of 80 my invention.

I do not limit my invention to the exact details of construction and arrangement of parts as shown and described in the foregoing, but my invention may be limited only 85 by a reasonable interpretation of the appended claims.

I desire to call special attention to the fact that I have provided means for operating my wind mill manually or otherwise 90 when there is insufficient wind current to accomplish this result and I therefore call particular attention to the showing made in Fig. 1 of the drawings wherein it will be observed that the rod 55 is shown as pivotally connected to the rocking beam of my wind mill, which will thus enable the operator to strongly push upward as well as to draw downward incident to the operation of the parts. By this means I am enabled 95 to positively actuate my wind mill whereby the rocking movement may be readily and easily accomplished and the pumping operation consummated as perfectly as when operated by the force of the wind. It will 100 further more be obvious that the said rigid rod may be operatively connected with any suitable form of motor designed for this purpose. Moreover said form of rigid control will be useful in initially starting or 105 overcoming the inertia of starting the machine by the wind.

What I claim:—

1. In a wind motor, a rocker, a horizontal beam carried by the rocker and supporting two constantly vertical and shiftable sails in normally balanced relation and adapted to be oscillated in a vertical plane by a wind current blowing at right angles to the plane of oscillation, and means operated by the oscillatory motion of the beam for shifting the sails and thereby reversing the oscillatory stroke of the beam. 115

2. In a wind motor, a normally horizontal beam supported at its middle portion and carrying two similar vertical sails at its opposite ends, said sails comprising shiftable blades, gravity operated means connecting all of the blades for shifting those of the respective sails into oppositely inclined 120 125 130

planes and in synchronism, and means co-acting with the first said means for exerting a tension on all of the blades and thereby retarding their shifting motion, said sails being adapted to be oscillated vertically by the action of the wind and in a plane at right angles to the direction of the wind.

3. In a wind motor, a horizontal beam balanced at its middle portion, shiftable sail members carried by the beam and adapted to coact with a wind current for causing the beam to oscillate, means coacting with the oscillatory beam for shifting the sail members, a vane associated with the beam for holding it at right angles to the wind current, and an auxiliary vane secured rigidly on the free end of the first said vane and disposed at right angles thereto and to the direction of the wind current.

20 4. In a wind motor, a beam, sails on the beam adapted to be moved by a current of wind, a vane for holding the sails in operative relation to the wind, said vane comprising a plate disposed parallel with the wind current and a plate rigidly secured on the free end of the first said plate at right angles thereto and to said wind current.

5. In a wind motor, a beam, sails on the beam adapted to be moved by a wind current, a vane for holding the sails in operative relation to the wind, said vane comprising a plate disposed parallel with the wind current, and an auxiliary vertical plate rigidly secured to the first said plate and at

right angles thereto and serving as an air cushioning element for steadyng the first said vane.

6. In a wind motor, a sail having pivoted blades adapted to be moved by a wind current, said blades consisting of thin strips of wood perforated near their ends and hooked pivot-members each engaging with one of the apertures of the blades, each pivot member extending along the edge of the blade and beyond the end thereof, and a binding member passing across the blade and embracing the pivot members.

7. In a motor of the class described, the combination with a pair of sails having a plurality of blades, truss bars carrying the blades, and means associated therewith for swinging said blades, of a pivotally mounted lever having one of its ends in contact with the blade controlling means, a plate adapted to be actuated by the wind for actuating the lever and thereby retarding the swinging movement of the blade, and means for adjustably securing said plate to the lever whereby the force of the leverage exerted may be increased or decreased.

In testimony whereof I have signed my name to this specification in the presence of two subscribing witnesses.

CHARLES McGREGOR.
